J. E. LE BUS

ROTARY PUMP

Filed Oct. 11, 1927

UNITED STATES PATENT OFFICE.

JOHN E. LE BUS, OF ELECTRA, TEXAS, ASSIGNOR OF ONE-SIXTH TO WILLIAM CALVERT, ONE-SIXTH TO J. H. HOWELL, ONE-SIXTH TO L. D. EMBRY, ONE-SIXTH TO GUS M. HAMER, AND ONE-SIXTH TO A. L. ROBB.

ROTARY PUMP.

Application filed October 11, 1927. Serial No. 225,509.

This invention relates to a rotary pump for oil wells.

An object of the invention is the provision of a device for pumping oil wells or wells containing water in any stage of development and at any depth, the pump in the case of oil wells being sufficiently effective that bailing is eliminated and the pumping may be done without setting the usual casing.

10 Another object of the invention is the provision of a pump which is capable of removing water from oil wells and also for removing mud from the hole when said mud is being pumped directly into the slush pit.

15 Another object of the invention is the provision of a simple and effective construction which may be placed in an oil well for bailing the water and for removing mud from the hole, means being employed in the pump for 20 automatically closing the circulation through the pump when desired, circulation being again created at will.

This invention will be best understood from a consideration of the following detailed description in connection with the accompanying drawings, nevertheless it is to be understood that the invention is not confined to the disclosure being susceptible of such changes and modifications as shall define no material 30 departure from the salient features of the invention as expressed in the appended claims.

In the drawings:—

Figure 1 is a vertical section of the pump shown in an operative position,

35 Figure 2 is a similar vertical section showing the pump in position with the circulation closed,

Figure 3 is a view in elevation of a seating shoe of the pump,

40 Figure 4 is a horizontal section taken along the line 4—4 of Fig. 2,

Figure 5 is a view in perspective of a yoke causing rotation and likewise reciprocation of the pump plunger.

45 Referring more particularly to the drawings 10 designates the top working barrel of the pump which is threaded at 11 in a swivel head or collar 12 and forming part of a race with a second collar 13 having a ball bearing

50 14. A packing gland 15 is threaded at 16 into a main body of the pump 17, the inner end of the packing gland resting upon ball bearings

18 which are carried by a recess formed in the collar or swivel head 12.

A combined packing nut and gland 20 is 55 threaded at 21 into the collar 15 and has threaded engagement with a nut 22, as shown at 23. A gasket 24 is seated within a pocket in the gland 20 and held in place by the nut 22. A second packing 25 is seated within a 60 pocket in the packing gland 15 and is maintained in place by combined packing gland and nut 20.

A mandrel 30 has an axial passage 31 extending longitudinally thereof, said mandrel being slidably mounted within the top working barrel 10. Keys 32 secured to the inner wall of the barrel 10 are adapted to ride within slots 33 formed in the mandrel 30 so that when the top barrel 10 is rotated the mandrel 70 30 will likewise be rotated but will be permitted to have a longitudinal movement in the working barrel. The inner end of the mandrel is provided with an internally threaded pocket 35 adapted to receive the 75 threads of a hollow boss 36 formed integrally with a hollow screw 37. A packing 38 is received within an annular groove in the mandrel 30 and is held in place by a nut 39 threaded onto the outer end of the mandrel. 80 The screw 37 is provided with right and left hand threads respectively, designated by the numerals 40 and 41, which are adapted to be engaged by a yoke 42 carried by an arm 43 mounted in a passage 44 in the retainer or 85 collar 13. Set screws 45 are adapted to secure the retainer 13 to the main body of the pump 17. A working barrel 46 embraces the screw 37 and is adapted to receive a plunger 47 which has an internally recessed portion 90 received by the threads of an inner reduced hollow boss 48 of the screw 37. The plunger 47 is provided with an annular groove to receive a packing ring 49 which is held in place on the plunger by means of a nut 50. The plunger has a passage 51 which is in open communication with the passage 52 in the screw 37 which in turn aligns with the passage 31 in the mandrel 30. The lower end of the plunger is provided with a pocket 53. 100

Threaded into the inner end of the pocket 53 is a valve cage 54 having a plurality of radial passages 55 which connect the interior of the working barrel 46 with the chamber 56

of the valve cage 54. A stem 57 is slidably mounted in the inner closed end 58 of the cage and carries at its upper end a valve 59 which is adapted to engage a seat 60 on the outer open end of the cage.

A disc 61 is rotatably mounted within a seat 62 in a sleeve 63 and is held in place by being rigidly engaged by the lower end of the working barrel 46 while the outer end of said working barrel is screwed into the inner end of the retainer 13. This disc is provided with a plurality of perforations 64 which will permit the passage of fluid between the hollow sleeve 63 and the working barrel 46. This disc also is adapted to engage the inner end of the stem 57 for moving and retaining the valve 59 from its seat as will be presently explained.

The wall of the sleeve 63 is of sufficient width to provide for a plurality of vertical passages 65 which extend from the inner end of the sleeve to an annular passage 66 at the outer end of said sleeve. The passage 66 is so formed that a head or closure 67 is provided at the outer end of the sleeve 63 and which is adapted to support the disc 61. This sleeve has a central passage 68 which extends from the inner end of the sleeve to the annular passage 66 and is in communication with the last named passage. Pipes 69 are slidably mounted in the passages 65 and are maintained in engagement at their inner ends with a partition 70 formed in a seating shoe 71 by springs 72.

A pipe 73 is closed at its lower end with a conically shaped cap 74 and adjacent said end is provided with a plurality of perforations 75 for placing the pipe in communication with the well. The upper end of the pipe, as shown at 76, is threaded into the central passage 68 of the sleeve 63. A valve cage 77 is threaded at 78 into the upper outer end of the pipe 73 and has a central passage 79 placing the passage 68 in communication with the pipe 73. A stem 80 is slidably mounted in the cage and carries at its upper end a valve 81 adapted to engage a seat 82 carried by the outer end of the cage 77.

The seating shoe, as shown at 84, is conically shaped and is so formed that it will neatly fit the bottom of a well when desired. Pins 85 are secured in the sleeve 63 at diametrically opposite points and adapted to engage slots 86 formed in the side wall of the member 71. The lower end of the shoe is closed, as shown at 87 and is provided with a plurality of passages into which are secured wash pipes 88. These pipes extend downwardly in parallel relation with the pipes 73 and are adapted to place the well in communication with a chamber 89 formed in the shoe 71.

A collar 90 has threaded engagement, as shown at 91 and 92, respectively, with the main body 17 of the pump and the sleeve 63

whereby the sleeve is rigidly connected with the body.

The operation of my device is as follows: When it is desired to wash the well in the usual manner the string of pipe are connected with the upper working barrel 10 and are slowly rotated whereby the upper working barrel is rotated as is the mandrel 30 and the screw 37. This causes the plunger 47 to move downwardly whereby the inner end of the stem 56 will engage the disc 61 and force the valve 59 from its seat. Water is then turned on which will flow down through the barrel 10, the passages 31, 52, and 51 through the valve cage and perforations 64 in the disc 61 through the annular passage 66, the vertical passages 65, the tubes 69, chamber 89 and pipes 88 to the exterior of the well. This water is withdrawn through the perforations 75, pipes 73 past valve 81 and then through the hollow plunger 47 and mandrel 30 to the working barrel 10.

When it is desired to cut off such circulation it is only necessary to lower the pumping device until the shoe 84 rests on the bottom of the well whence the weight will cause the parts above said shoe to settle whereby the pins 85 will ride in the inclined slots 86 and sufficiently rotate the shoe 71 to cause the pipes 69 to ride over the surface of the partition 70 and place the lower ends of the pipes out of alignment with the passages 100 in the partition 70. During pumping of the well or during bailing it is only necessary to rotate the working barrel 10 whereby the mandrel 30 will not only be revolved with the working barrel, but due to the fact that yoke 42 engages the right and left hand threads of the screw 37, the screw will be reciprocated in opposite directions, as will be the plunger 47 and its packing 49, due to the fact that the keys 32 will permit reciprocation of the mandrel and also rotation of the same. During the reciprocation of the pump while being rotated, fluid will be drawn upwardly and forced out from the barrel 46 through the passages 55 in the valve casing, past valve 59 and through passages 51, 52 and 31. At this time the valve 59 is opened and closed alternately as the plunger is reciprocated. During normal operation of the pump the shoe 71 is seated on the bottom of the well so that the fluid is drawn through perforations 75 in the pipe 73 and past valve 81.

I claim:

1. A pump comprising a tubular body, a pump cylinder in the body and supported by said body, a working barrel mounted for rotation in the body, a mandrel adapted to be rotated by the barrel, means for causing reciprocation of the mandrel when the same is rotated, a plunger connected with the mandrel, and a valve for controlling the flow of liquid to the cylinder, said mandrel and

plunger each being provided with a passage for pumped liquid.

2. A pump comprising a tubular body, a pump cylinder in the body and supported by said body, a working barrel mounted for rotation in the body, a mandrel adapted to be rotated by the barrel, means for causing reciprocation of the mandrel when the same is rotated, a plunger connected with the mandrel, a valve for controlling the flow of liquid to the cylinder, and means for opening the valve and for maintaining said valve in open position when desired, said mandrel and plunger each being provided with a passage for pumped liquid.

3. A pump comprising a tubular body, a pump cylinder in the body and supported by said body, a working barrel mounted for rotation in the body, a mandrel adapted to be rotated by the barrel, means for causing reciprocation of the mandrel when the same is rotated, a plunger connected with the mandrel, a valve for controlling the flow of liquid to the cylinder, a hollow seating shoe connected with the body; a valve in the shoe for controlling the flow of liquid to the tubular body, said mandrel and plunger each being provided with a passage for pumped liquid.

4. A pump comprising a tubular body, a pump cylinder in the body and supported by said body, a working barrel mounted for rotation in the body, a mandrel adapted to be rotated by the barrel, means for causing reciprocation of the mandrel when the same is rotated, a plunger connected with the mandrel, a valve for controlling the flow of liquid to the cylinder, and means for opening the valve and for maintaining said valve in open position when desired, a valve in the tubular body, located inwardly of the first mentioned valve, and controlling the flow of the liquid to the first mentioned valve, said mandrel and plunger each being provided with a passage for pumped liquid.

5. A pump comprising a tubular body, a pump cylinder in the body and supported by said body, a working barrel mounted for rotation in the body, a mandrel adapted to be rotated by the barrel, means for causing reciprocation of the mandrel when the same is rotated, a plunger connected with the mandrel, a valve for controlling the flow of liquid to the cylinder, a hollow seating shoe connected with the tubular body and provided with a transverse partition having openings therein, pipes adapted to register with the openings, means for causing rotation of the shoe to displace the opening relative to the pipes for cutting off communication between the cylinder and outer end of the shoe, said mandrel and plunger each being provided with a passage for pumped liquid.

6. A pump comprising a tubular body, a pump cylinder in the body and supported by said body, a working barrel mounted for ro-

tation in the body, a plunger mounted for sliding and rotary motion in the cylinder, means connecting the plunger with the working barrel and for causing reciprocation of the plunger when the barrel is rotated, a suction valve in the cylinder controlling the flow of liquids through said cylinder, and means adapted to open and retain the valve open when the plunger is moved to an inward position, said plunger having a passage for pumped liquid.

7. A pump comprising a tubular body, a pump cylinder in the body and supported by said body, a working barrel mounted for rotation in the body, a plunger mounted for sliding and rotary motion in the cylinder, means connecting the plunger with the working barrel and for causing reciprocation of the plunger when the barrel is rotated, a suction valve in the cylinder controlling the flow of liquids through said cylinder, means adapted to open and retain the valve open when the plunger is moved to an inward position, a seating shoe, a sleeve connecting the shoe with the body member, said sleeve being in communication with the cylinder, a pipe carried by the sleeve and extending through the shoe, a valve in the pipe for controlling communication between the pipe and the cylinder, and means for controlling communication between the cylinder and shoe externally of the pipe, said plunger having a passage for pumped liquid.

8. A pump comprising a tubular body, a pump cylinder in the body and supported by said body, a working barrel mounted for rotation in the body, a plunger mounted for sliding and rotary motion in the cylinder, means connecting the plunger with the working barrel and for causing reciprocation of the plunger when the barrel is rotated, a suction valve in the cylinder controlling the flow of liquids through said cylinder, means adapted to open and retain the valve open when the plunger is moved to an inward position, a hollow shoe, a sleeve connecting the hollow shoe with the body member and being in communication with the cylinder, a plate axially disposed with respect to the seating shoe and placing the sleeve in communication with the exterior of the shoe, a valve for controlling communication between the pipe and the sleeve, said plunger having a passage for pumped liquid.

9. A pump comprising a tubular body, a pump cylinder in the body and supported by said body, a working barrel mounted for rotation in the body, a plunger mounted for sliding and rotary motion in the cylinder, means connecting the plunger with the working barrel and for causing reciprocation of the plunger when the barrel is rotated, a suction valve in the cylinder controlling the flow of liquids through said cylinder, means adapted to open and retain the valve open when the

plunger is moved to an inward position, a hollow shoe, a sleeve connecting the hollow shoe with the body member and being in communication with the cylinder, a plate axially disposed with respect to the seating shoe and placing the sleeve in communication with the exterior of the shoe, a valve for controlling communication between the pipe and the sleeve, a partition in the shoe dividing the shoe into a pair of chambers and provided with a plurality of passages, tubes slidably mounted in the sleeve and adapted to align with the passages in the partition for placing the sleeve in communication with the shoe externally of the pipe, said plunger having a passage for pumped liquid.

10. A pump comprising a tubular body, a pump cylinder in the body and supported by said body, a working barrel mounted for rotation in the body, a plunger mounted for sliding and rotary motion in the cylinder, means connecting the plunger with the working barrel and for causing reciprocation of the plunger when the barrel is rotated, a 20 suction valve in the cylinder controlling the flow of liquids through said cylinder, means adapted to open and retain the valve open when the plunger is moved to an inward position, a hollow shoe, a sleeve connecting the hollow shoe with the body member and being in communication with the cylinder, a plate axially disposed with respect to the seating shoe and placing the sleeve in communication with the exterior of the shoe, a valve for controlling communication between the pipe and the sleeve, a partition in the shoe dividing the shoe into a pair of chambers and provided with a plurality of passages, tubes slidably mounted in the sleeve and adapted to align 30 with the passages in the partition for placing the sleeve in communication with the shoe externally of the pipe, means for causing rotation of the shoe for disalining the tubes with the passages and cutting off the communication between the sleeve and one of the chambers of the shoe, a plurality of tubes for placing the outer end of the shoe in communication with the exterior of said shoe, said pipe having a closed end provided with a plurality of perforations where said pipe projects beyond the end of the shoe, said plunger having a passage for pumped liquid.

35

40

nication between the sleeve and one of the 45 chambers of the shoe, said plunger having a passage for pumped liquid.

11. A pump comprising a tubular body, a pump cylinder in the body and supported by said body, a working barrel mounted for rotation in the body, a plunger mounted for sliding and rotary motion in the cylinder, means connecting the plunger with the working barrel and for causing reciprocation of the plunger when the barrel is rotated, a 50 suction valve in the cylinder controlling the flow of liquids through said cylinder, means adapted to open and retain the valve open when the plunger is moved to an inward position, a hollow shoe, a sleeve connecting the 55 hollow shoe with the body member and being in communication with the cylinder, a plate axially disposed with respect to the seating shoe and placing the sleeve in communication with the exterior of the shoe, a valve for controlling communication between the pipe and the sleeve, a partition in the shoe dividing the shoe into a pair of chambers and provided with a plurality of passages, tubes slidably mounted in the sleeve and adapted to align 60 with the passages in the partition for placing the sleeve in communication with the shoe externally of the pipe, means for causing rotation of the shoe for disalining the tubes with the 65 passages and cutting off the communication between the sleeve and one of the chambers of the shoe, a plurality of tubes for placing the outer end of the shoe in communication with the exterior of said shoe, said pipe having a closed end provided with a plurality of perforations where said pipe projects beyond the end of the shoe, said plunger having a passage for pumped liquid.

Signed at Electra, in the county of Wichita and State of Texas, this 8th day of October, 85 A. D. 1927.

JOHN E. LE BUS.
